REMSEN F. POST, OF NEW YORK, N. Y., ASSIGNOR TO JOSEPH B. LEVY, OF JAMAICA,
NEW YORK

DESIGN FOR A COMBINED ELECTRIC READING LAMP AND PENCIL HOLDER

Application filed November 17, 1928. Serial No. 28,924. Term of patent 3½ years.

To all whom it may concern:

Be it known that I, REMSEN F. Post, a citizen of the United States, residing at New York, in the county of New York, and State of New York, have invented a new, original, and ornamental Design for a Combined Electric Reading Lamp and Pencil Holder, of which the following is a specification, reference being had to the accompanying drawing, forming part thereof.

Fig. 1 is a front elevational view of a com-

bined electric reading lamp and pencil holder, showing my new design.

Fig. 2 is an end elevational view of the same.

Fig. 3 is a plan view of the same.

I claim:

The ornamental design for a combined electric reading lamp and pencil holder, as shown.

In testimony whereof I have affixed my signature.

REMSEN F. POST.
